(57) **CLAIM**

The ornamental design for a bobber and rig, as shown and described.

DESCRIPTION

The design is for a bobber comprising a bobber body, and a rig. A rig comprises a bobber body, bobber leader, a bobber stop, a weight and a hook.

FIG. 1 is a top view of a bobber showing an embodiment of the design of this invention.

FIG. 2 is a side view thereof, the opposite side being symmetrical.

FIG. 3 is a bottom view thereof.

FIG. 4 is a cross sectional view thereof taken along line 4—4 of FIG. 2.

FIG. 5 is a first perspective view thereof.

FIG. 6 is a second perspective view thereof.

FIG. 7 is a perspective view of a bobber showing an alternative embodiment of the design, other views of the bobber body thereof being identical to those shown in FIGS. 1–6 above.

FIG. 8 is a perspective view of a bobber showing an alternative embodiment of the design, other views of the bobber body thereof being identical to those shown in FIGS. 1–6 above; and,

FIG. 9 is a perspective view of a bobber showing an alternative embodiment of the design, other views of the bobber body thereof being identical to those shown in FIGS. 1–6 above.

The broken line showing of environment in the drawings is for illustrative purposes only and forms no part of the claimed design.
